UNITED STATES PATENT OFFICE.

THOMAS W. ESTES, OF NEW YORK, N. Y., ASSIGNOR TO ESTES & BLUM, INC., OF NEW YORK, N. Y., A CORPORATION OF NEW YORK.

DESIGN FOR A TEXTILE FABRIC.

Application filed May 4, 1925. Serial No. 13,319. Term of patent 3½ years.

To all whom it may concern:

Be it known that I, THOMAS W. ESTES, a citizen of the United States of America, residing at New York, in the county of New York and State of New York, have invented a new, original, and ornamental Design for a Textile Fabric, of which the following is a specification, reference being had to the accompanying drawing, forming a part thereof.

The figure is a plan view of a piece of textile fabric showing my new design.

I claim:

The ornamental design for a textile fabric as shown.

THOMAS W. ESTES.
